CLAIM

The ornamental design for a pull toy, as shown and described.

DESCRIPTION

FIG. 1 is a perspective view of a pull toy showing my new design;

FIG. 2 is a top plan view;

FIG. 3 is an end elevational view as seen from the left of FIG. 1;

FIG. 4 is a side elevational view; and

FIG. 5 is a bottom plan view.

The side not shown is identical to that shown.
